CLAIM

The ornamental design for a pickup topper, as shown
and described.

DESCRIPTION

FIG. 1 is a top rear perspective view of a pickup topper
showing my new design;

FIG. 2 is a top plan view thereof;

FIG. 3 is a front elevational view thereof;

FIG. 4 is a rear elevational view thereof;

FIG. 5 is a side elevational view thereof, the opposite
side being a mirror image of the side shown; and

FIG. 6 is a bottom plan view thereof.
